(57)

CLAIM

The ornamental design for an unmanned aerial vehicle, as shown and described.

DESCRIPTION

FIG. 1 is a front elevation view of an unmanned aerial vehicle showing ap the claimed design.

FIG. 2 is a back elevation view thereof.

FIG. 3 is a top plan view thereof.

FIG. 4 is a bottom plan view thereof.

FIG. 5 is a left side elevation view thereof.

FIG. 6 is a right side elevation view thereof.

FIG. 7 is a top-left-front isometric view thereof; and,

FIG. 8 is a top-right-back isometric view thereof.

The broken lines depict portions of the unmanned aerial vehicle that form no part of the claimed design.
